[57] ABSTRACT

A wave generating apparatus particularly adapted for use in studying wave phenomena having a plurality of wave source means mounted above a ripple tank and reciprocated vertically by a pair of pivotally mounted parallel rocker arm means to produce waves in the surface of the fluid in the ripple tank. The means driving the rocker arms are adjustable with respect to the rocker arms to vary the amplitude of the waves produced and may be regulated by control means in electrical communication with them to vary the frequency and phase of the waves produced. The bottom of the ripple tank is sloped upwardly from its center to effectively damp the waves in at least one direction. The wave generator and ripple tank may be used in combination with an overhead projector or an overhead light source so that images of the waves produced are projected upon an easily visible plane surface.

**WAVE GENERATING APPARATUS FOR STUDY OF
WAVE PHENOMENA**

BACKGROUND OF THE INVENTION

This invention relates to an apparatus for generating waves of variable frequency, phase and amplitude for studying wave phenomena.

The use of wave generators as a teaching tool is well recognized. Such generators are often used to produce waves allowing the students to study the phenomena of reflection, defraction, refraction and interference in a laboratory setting. Previous generators, however, have often been limited in their use and desirability by their high cost and cumbersome construction, their lack of flexibility in performing multiple source variations of the standard tests, and their inability to illustrate additional wave phenomena such as phase.

Recent constructions of wave generating apparatus are shown in related U.S. Pat. Nos. 3,253,353 and 3,276,614 to J. G. Steed et al. While Steed et al teach a device which provides for variation of the frequency and phase relationship of the point sources, this device still contains several undesirable disadvantages. The Steed et al apparatus is limited to only two point sources, yet it is often desirable to have more than two point sources and to be able to vary the number of point sources easily. There is no suggestion in Steed et al of any means for increasing the number of wave sources, since there is only a single motor. Further, Steed et al teach a complex mechanical means of varying the phase and speed of the motor, which is subject to abuse and breakdown. In addition, wave images are projected below the ripple tank making observation by a large group or photographing difficult. Finally, there is no provision in the prior art of a means of damping waves to prevent reflections off the side of the ripple tank, or of easily regulating the level of the fluid in the ripple tank.

DESCRIPTION OF THE INVENTION

The present invention allows simultaneous variation and control of the frequency, phase and amplitude of waves generated from a variable number of point sources in a ripple tank constructed to eliminate interference by waves reflected from the sides of the tank. This invention overcomes the disadvantages of the prior art by a wave generator having vertical support means held in spaced relationship by and supporting a horizontal support means which may be positioned above a projecting screen of an overhead projector or below a light source. The vertical support means are bridged by a pair of parallel rocker arms pivotal on them and extending along the length of the horizontal support means. Mounted on the horizontal support means and below these rocker arms are a variable number of wave point source means upwardly biased against the bottom of the rocker arms and movable in a vertical reciprocal fashion upon pivotal movement of the rocker arms. The rocker arms are independently connected by drive means mounted on one vertical support to dual motor means, each of which drive one of the rocker arms.

The drive means includes a pair of rod means connected at their upper ends to an outwardly extending flange on each rocker arm, and, at their lower ends, to a ring moved by an eccentric driven by a pulley reduc-

tion system which is, in turn, driven by a motor. Each rod is independently adjustable in its stroke to vary the movement of its rocker arm, the displacement of the wave point sources moved by the rocker arm, and, thereby, the amplitude of the wave produced.

The motors are connected to a source of electrical power and have a rheostat interposed between them to provide electrical control over the phase between the waves produced by the rocker arms, and a rheostat in parallel with them across the source of electrical power to provide electrical control of the frequency of the waves by varying the speed of the motor.

This invention, therefore, provides simple, yet novel means to control phase, frequency and amplitude. It eliminates the complex mechanical gearing previously required to vary these aspects of the waves. This wave generating apparatus is constructed so that it may be used in combination with an overhead projector to allow images of the waves produced to be projected on a plane surface, such as the wall, for photographing and extended study of the various phenomena. The uniquely constructed ripple tank effectively damps out secondary wave reflections from its walls because of its tapered bottom and allows easy variation of the fluid level. The variable number of point sources made available for use in the novel construction of this invention significantly increases the number of experiments which may be conducted and eliminates the inflexibility of previous devices.

Accordingly, it is an object of this invention to provide a wave generating apparatus that is simple and inexpensive in construction and allows great flexibility in the number and types of experiments in which it is useful.

It is another object of this invention to provide a wave generating apparatus which allows electrical variation and control of the phase and frequency of waves produced and mechanical variation and control of the amplitude of such waves.

It is a further object of this invention to provide a wave generating apparatus which permits the use of a plurality of wave sources.

It is still another object of this invention to provide a wave generating apparatus which has an easily variable number of wave point sources, any two groups of which may be varied in phase relationship between zero and 180°.

It is a still further object of this invention to provide a wave generating apparatus which is particularly useful in connection with an overhead projector to project wave images on a plane surface.

It is also an object of this invention to provide a wave generating apparatus having a ripple tank which substantially eliminates the secondary reflection due to waves bounced off the walls of the tank.

It is also another object of this invention to provide a wave generating apparatus having a ripple tank which allows the level of the fluid in the tank to be easily varied.

These and other objects of this invention will become apparent from the following description of the drawings illustrating a preferred embodiment wherein:

FIG. 1 is a perspective view of the wave generating apparatus of this invention as used in combination with an overhead projector;

FIG. 2 is a front elevational view of the wave generating apparatus shown in FIG. 1;

FIG. 3 is a top view of the wave generator alone; FIG. 4 is an end elevational view of the wave generator alone taken generally along line 4—4 in FIG. 2;

FIG. 5 is a cross-sectional elevational view of the wave generator of this invention taken generally along line 5—5 of FIG. 2;

FIG. 6 is a schematic view of a possible embodiment of the control and drive circuitry of the wave generating apparatus shown in FIG. 2;

FIG. 7 is a top plan view of the ripple tank shown in FIG. 2; and,

FIG. 8 is a cross-sectional end elevational view of the ripple tank taken generally along line 8—8 of FIG. 7.

Referring now to the drawings and in particular to FIG. 1, the wave generating apparatus of this invention is shown generally at 10. This wave generating apparatus 10 is positioned for use in combination with a conventional overhead projector 12 having a horizontal projection screen 13 and an image projecting means 15, normally including a number of mirrors or lenses to rectify and project the focused image on a vertical screen.

The wave generating apparatus 10 includes a wave generator 14 and a ripple tank 16 which contains a fluid media, such as water, in which wave phenomena may be produced.

The wave generator 14 has, at its opposite ends, vertical support means or legs 18 which may be integrally molded of a sufficient length to support the wave generator 14 above the floor. Thus, the wave generator 14 need not be mounted on the overhead projector and is easily movable so that it may be used with overhead light sources to project a horizontal image, if desired. The vertical support legs 18 are positioned on opposite sides of the rectangular ripple tank 16 and have, mounted between them, parallel horizontal support means or bars 20 disposed in vertical alignment, one above the other, as shown more clearly in FIG. 2.

A pair of rocker arms 22 and 24 are mounted in parallel relationship to the horizontal bars 20, on pivotal connections 26 at either end of the vertical support legs 18. These rocker arms, which are disposed in mirror-image relationship will be referred to as the first rocker arm 22 and the second rocker arm 24, respectively. They are constructed of angles disposed along the length of the support bars 20 and above the support bars, having at either end a centrally extending flange 27, as shown in FIG. 4, by which they may be mounted for pivotal movement with respect to the vertical legs 18 and the horizontal bars 20 by connections 26. The rocker arms 22 and 24 are disposed so that the downwardlyextending leg of each angle is positioned to the outside to engage the top of the wave point sources 28, which reciprocate to produce the desired waves in the fluid media.

As shown in FIGS. 1 and 2, each wave point source 28 includes a vertical plunger rod 30 which is held in a vertical position and mounted for reciprocal movement in a mounting block 32. The mounting block 32 is shaped so that it has an enlarged portion having a bore therethrough for receiving the plunger 32, which extends beyond the edges of the lower horizontal bar 20, and a narrower body portion formed to fit in the mounting space between the upper and lower horizontal support bars 20. A fastening means 34, such as a machine screw and large washer is disposed on the op-

posite side of this body portion, as shown in FIG. 2, to be tightened against the sides of the upper and lower support bars 20 to firmly mount each wave point source assembly 28 in position between the bars. At the lower end of the plunger 30 is mounted a foot 36, having its bottom surface in contact with the surface of fluid 17. The reciprocal movement of this foot 36 generates the waves in the fluid. A spring 38 is disposed around the circumference of the plunger rod 30 between the mounting block 32 and a retaining head 39 to urge the plunger rod 30 and attached foot 36 to an upward position.

It may be seen by reference to the drawings that the wave point sources 28 may be mounted on opposite sides of the horizontal bars, if desired, and as many sources 28 as required in a particular experiment may be mounted along the length of the horizontal bars 20. This allows great flexibility in choosing the number of sources in a particular experiment and also in choosing a particular fixed position or point from which each source may generate a wave. This flexibility of location enables the operator to generate a number of waves having their sources at different points, both longitudinally and laterally of the ripple tank 16.

The plungers 30 of the wave point sources 28 are moved in a reciprocal fashion to produce the desired waves by the pivotal movement of the first and second rocker arms 22 and 24, respectively. The downwardly-extending flange of each rocker arm engages the heads 39 of the wave point source 28 disposed on its particular side and, in pivoting about the connection 26, reciprocates the plunger 30 a slight distance to create a disturbance on the fluid surface. This pivotal movement of the rocker arms 22 and 24 is caused by the generally-reciprocal movement of the drive rods 42 and 42' which engage horizontal and outwardly-extending rocker arm flanges 40 and 40' near their upper ends. This movement is caused by similar, but independent dual drive assemblies, operating each drive rod as will be described below.

Prime numerals are used to refer to parts of similar description in each drive assembly since each assembly has a similar construction and function. Only a single assembly will therefore be described. The drive rod 42 may be moved outwardly or laterally with respect to the rocker arm 22 in a rocker arm adjusting slot 44 to permit variation of the length of the lever arm used to move the rocker arm 22 around the pivot point 26. Outward movement will increase the length of this lever arm and thus decrease the vertical component of movement of the flange and the corresponding amplitude of the wave produced by movement of the wave source 28. Conversely, inward movement of the drive rod 42 in slot 44 will increase the amplitude of the wave. Whenever the drive rod 42 is moved in adjusting slot 44, a drive rod head 46 may be moved upwardly or downwardly on a threaded portion of drive rod 42 so that the rocker arm flange 40 and rocker arm 22 are maintained in a horizontal position to assure accurate variation of amplitude.

The drive rod 42 is driven in reciprocal fashion by a drive assembly, shown generally at 48, which is mounted on a support means 50 which may be mounted directly on vertical supports 18 or attached thereto by rigid mounting means 52, as shown in FIG. 2. The drive assembly 48 consists of a direct current motor means 54 mounted near the bottom and outward

of the support means 50. This motor means 54, upon actuation, rotates a drive pulley 56 around the central axis of the motor means. Drive pulley 56 is connected by a belt 57 to a reduction pulley 58, which effectively reduces the direct rotational speed of the motor means 54 to a speed acceptable for use in this wave generating apparatus. The reduction pulley 58 is rotated about a central axis 59 by this arrangement. Mounted on the central axis 59, for rotation therewith, is an eccentric 60. Disposed about the circumference of the eccentric 60 is a drive rod mounting ring 62, having a radial hole or bore formed at one point on its circumference. This hole or bore receives the lower end of the drive rod 42 and holds it firmly in a fixed relationship. The drive rod 42 also passes through a bore in a rod guide and adjusting means 66 near its middle portion. This rod guide and adjusting means 66 is mounted on the support means 50 in an amplitude adjusting slot 64 extending laterally of the support means 50 and the rocker arms 22 and 24, to assist in permitting lateral movement of the drive rod 42 to vary the length of the lever arm of the rocker arm and thereby the amplitude of the waves produced. The rod guide and adjusting means 66 maintains rod 42 in a set angular position with respect to the vertical axis through central axis 59 while allowing rod 42 to move freely in a reciprocal fashion within it.

By this arrangement, the eccentric 60, as it rotates freely within the drive rod mounting ring 62, will move the ring 62 upwardly or in reciprocal fashion as it makes a complete revolution, as shown in FIG. 5, where motors 54 and 54' are approximately 180° out of phase, thus causing the eccentric 60 and 60' and their respective drive rods to be in opposite positions.

In addition to mechanical control of the amplitude, control of the phase and frequency are accomplished by control of the motor means 54 and 54' by a simple circuit of the type shown in FIG. 6. This electrical circuit includes a 3 to 6 volt battery 70 in electrical communication by suitable electrical conduit means 71 through one terminal with a rheostat 72 connected in series with the motors 54 and 54' and variable to increase or decrease their speed and thus the frequency of the wave fronts produced. The other terminal of battery 70 is connected by conduit means 71 to a similar rheostat 74 which is connected between or in parallel with the motors 54 and 54' vary the current and power in each motor circuit and thus the phase of the waves. If rheostat 74 is moved so that the resistances in each motor circuit are equal, the motors will run in phase. In this condition, the lines of interference formed by waves from more than one point source will appear to be stationary. If the resistances are made unequal, however, the interference lines will begin to rotate. Rotation will appear to occur in the direction of the point sources reciprocated by the motor receiving the most power.

The ripple tank 16 is shown in detail in FIGS. 7 and 8. It is formed of continuous side walls 78 which are fluid-tightly joined to a bottom wall 80. The bottom wall 80 is sloped upwardly from its center point so that waves moving toward the short or lateral sides of the tank will be effectively damped out and not create reflected interference waves which would interfere with the conduct and observation of the experiment. The tank 16 is preferably rectangular to permit extended travel of a wave in one direction to allow observation

of its motion. It is clear that the tank 16 could also be formed of a continuous circular side wall having a frusto-conical shaped bottom wall fluid-tightly sealed to it. A trough 81 is formed out of one section of the bottom wall 80 so that the bottom is horizontal in that particular section. This allows water to be easily evacuated from the tank to a liquid reservoir, so that by vertical movement of the liquid reservoir, the level of liquid in the tank 16 may be raised or lowered without having to add or drain water from the ripple tank itself. The level of the fluid media 17, however, should always be approximately at or below the intersection of the side and bottom walls if effective damping is to be achieved.

The foot 36 of each wave point source 28 is preferably not actually immersed in the fluid 17, and does not break the surface of the fluid in its upward movement. The wave point sources 28 and the feet 36 should be positioned with respect to the surface of the fluid 17 so that the foot 36 contacts the surface in its lowest position. Thus, when the plunger 30 and foot 36 are reciprocated slightly upward by the action of the drive assembly and the resulting pivotal movement of the rocker arms, the tendency of the fluid used, such as water, to adhere to the broad bottom surface of the foot 36 will create a sufficient disturbance to cause a wave, yet not a great enough disturbance to disrupt the wave pattern or produce undesirable results.

The materials which may be used in constructing this invention include any suitable material which may be easily cleaned, resists corrosion, and may be formed or bored as desired including brass, aluminum, steel and steel alloys.

While this invention has been described in relation to preferred embodiments thereof, it will be apparent to those skilled in the art that the structural details are capable of wide variation without departing from the principles of the invention.

I claim:

1. A wave generating apparatus particularly adapted for use in studying wave phenomena including a tank means adapted to receive a liquid, a wave generator having a first support means, second support means joined to said first support means in spaced relationship above said liquid in said tank means, rocker arm means mounted on and between said first support means for pivotal movement relative to said first support means, wave source means mounted on said second support means and disposed for operative engagement with said rocker arm means thereby to be reciprocally moved on movement of said rocker arm means, said wave source means having one end disposed for engagement with said liquid, drive means operatively engaging said rocker arm means to pivotally move said rocker arm means, control means to regulate the operation of said drive means and the movement of said rocker arm means, said tank means including side walls and a bottom wall sloping upwardly from its center and joined in fluid-tight relationship thereto and containing said liquid therein, said wave generator being operable to produce waves in said liquid which may be varied in frequency, phase and amplitude according to the operation of said control means and adjustment of said drive means.

2. The wave generating apparatus of claim 1 wherein said control means includes dual direct current motors, each of which is operatively connected to corresponding drive means to move said drive means indepen-

dently to thereby cause said rocker arm means to move with respect to said second support means.

3. The wave generating apparatus of claim 1 wherein said second support means includes horizontal bar means disposed in spaced relationship to dual rocker arms disposed in parallel relationship along said bar means on opposite sides thereof, each of said rocker arms being pivotal with respect to said bar means to move certain of said wave source means mounted thereon, said wave source means including at least one plunger reciprocally movable with respect to said bar means in the liquid contained in said tank means to create a point disturbance therein.

4. The wave generating apparatus of claim 1 wherein said wave source means includes a plurality of individual plungers mounted on said second support means and disposed along the length thereof for vertical reciprocal movement with respect thereto, one end of each of said plungers being biased into contact with said rocker arm means such that upon pivotal movement of said rocker arm means, said plunger is moved in the liquid contained in said tank means to create a point source disturbance therein, said plungers being mountable on opposite sides of said second support means as desired, such that variation in the phase of the waves produced thereby may be obtained upon movement of said rocker arm means as regulated by said control means.

5. The wave generating apparatus of claim 1 wherein said drive means includes dual, independent pulley reduction means rotatably mounted adjacent one another on said first support means, each of said reduction means having eccentric means mounted at the central axis thereof for rotation therewith, said eccentric means supporting one end of an upwardly-extending rod means, and, upon rotation of said reduction means, acting to move said rod means reciprocally relative to said second support means, said rod means being operatively engaged, near its upper end, with said rocker arm means such that movement of said rod means will cause said rocker arm means to be pivoted with respect to said second support means to move said wave source means.

6. The wave generating apparatus of claim 2 wherein said control means includes variable resistance means placed between said dual motor means such that when resistance is varied to decrease the electrical power supplied to one of said motor means, the electrical power supplied to the other of said motor means is correspondingly increased, any differences in electrical power supplied to the motor means causing the speeds of the respective motor means to vary proportionately, thereby varying the degree of phase between the waves produced by the drive means, rocker arm means and wave source means mechanically connected to and operated by the motor means.

7. The tank means of claim 1 wherein said side walls are integrally formed with said bottom wall, said bottom wall additionally having a trough means formed in its surface, said trough means having a generally flat bottom and being effective to allow the liquid level in the tank to be varied through an outlet means in communication with an outside liquid reservoir.

8. The wave generating apparatus of claim 1 wherein a portion of said drive means is movable laterally relative to said second support means and said rocker arm

means to vary the amplitude of waves produced by said wave generating apparatus.

9. The wave generating apparatus of claim 5 wherein each of said rod means is maintained in a generally upright position and in operative engagement with said eccentric means by holding means, said rod means being laterally movable with respect to said rocker arm means in slots formed in said first support means and said rocker arm means such that when said rod means is moved outwardly within said slots relative to said rocker arm means, the point of engagement of said rod means and said rocker arm means is moved outward on said rocker arm means relative to said second support means, thereby decreasing the amplitude of the waves produced by operation of the wave generating apparatus.

10. A wave generating apparatus particularly adapted for use with an overhead projector, including a wave generator positioned above the projection screen of the projector having vertical support means extending above the plane of the screen thereof, horizontal support means mounted on said vertical support means above the projection screen, rocker arm means mounted on said vertical support means for pivotal movement with respect to said vertical support means, wave source means mounted on said horizontal support means, and disposed in operative engagement with said rocker arm means to be reciprocally moved thereby, drive means moved by motor means and operatively engaging said rocker arm means to pivotally move said rocker arm means, said motor means being regulated in operation by control means, and including tank means disposed between the projection screen and said horizontal support means, said tank means having side walls and a bottom wall sloping upwardly from its center and joined in fluid-tight relationship thereto, said tank means containing a liquid such that upon movement of said drive means, said wave source means are moved reciprocally with respect to the surface of said liquid to produce waves in said liquid which may be varied in frequency, phase and amplitude by operation of said control means and adjustment of said drive means.

11. The wave generating apparatus of claim 10 wherein said vertical support means are disposed at opposite ends of said horizontal support means and are removably mounted on opposite sides of the projector screen, one of said vertical support means having a plate supporting said motor means and said drive means, said motor means being operatively connected to said drive means to move said drive means.

12. A wave generator providing for the simultaneous control of the phase, frequency and amplitude of waves produced thereby, including first support means, second support means joined to said first support means and maintained in spaced relationship above the surface of a liquid medium for the production of waves thereby, rocker arm means mounted on said first support means for pivotal movement relative to said first support means, wave source means mounted on said second support means and disposed for operative engagement with said rocker arm means, said wave source means having one end disposed for engagement with said liquid, drive means operatively engaging said rocker arm means and operable to pivotally move said rocker arm means thereby to reciprocally move said wave source means, said drive means being adjustable

relative to said second support means to vary the amplitude of the waves produced by movement of said wave source means relative to said liquid, and control means to regulate the operation of said drive means and the

movement of said rocker arm means and thereby vary the phase and frequency of waves produced by said wave generator.
